United States Patent Office

Des. 187,973
Patented May 17, 1960

187,973

BLANKET FABRIC OR SIMILAR ARTICLE

John N. Moeckel, Biddeford, Maine, assignor to Pepperell Manufacturing Company, Boston, Mass., a corporation of Massachusetts

Application June 12, 1957, Serial No. 46,554

Term of patent 14 years

(Cl. D92—2)

Fig. 1

I claim:

The ornamental design for a blanket fabric or similar article, substantially as shown.
